DESCRIPTION

U.S. PATENT DOCUMENTS

The FIGURE is a front view of a display screen or portion thereof with graphical user interface showing our new design.

2,027,952 A 1/1936 Bandoly
D119,256 S 3/1940 Darling
3,662,535 A 5/1972 Hedrick et al.
D229,436 S 11/1973 Chow
3,852,953 A 12/1974 Mischiatti
4,012,898 A 3/1977 Yoshizawa
4,063,735 A 12/1977 Wendel

The outermost broken lines in the FIGURE show a display screen or portion thereof, and form no part of the claimed design. The other broken lines in the FIGURE show portions of the graphical user interface that form no part of the claimed design.
